UNITED STATES PATENT OFFICE.

GEORGE R. STINE, OF LOS ANGELES, CALIFORNIA.

FOLDING FURNITURE.

1,367,437.

Specification of Letters Patent.

Patented Feb. 1, 1921.

Application filed February 24, 1920. Serial No. 360,790.

To all whom it may concern:

Be it known that I, GEORGE R. STINE, a citizen of the United States, residing at Los Angeles, in the county of Los Angeles and 5 State of California, have invented new and useful Improvements in Folding Furniture, of which the following is a specification.

This invention relates to folding furniture, and more particularly to a foldable 10 camping table.

One of the objects of the invention is to provide a foldable table, particularly adapted for picnic outings, camping, pleasure resorts, and the like, which is simple and substantial in construction and which may be quickly folded into a compact unit for shipment, storage or transportation, and just as readily extended or unfolded when required.

With the above and other objects in view, 20 the invention consists in the novel features of construction, combination and arrangement of parts to be hereinafter more fully described, claimed and illustrated in the accompanying drawings, in which—

25 Figure 1 is a side elevation of the table.

Fig. 2 is an end elevation.

Fig. 3 is a perspective view.

Fig. 4 is a bottom plan view, showing the legs and braces in position for folding.

30 Fig. 5 is a perspective view of the table when folded.

Referring to the drawings in detail, A indicates generally, a table top, comprising the leaf sections 10 and 11 and an intermediate 35 section 12, to which the leaf sections are connected by hinges 13.

To provide suitable foldable supports for the table a pair of arms 14 are connected by 40 hinges 15 to each section 10 and 11. These arms are adapted to fold inwardly, and between each pair there is provided a connecting member 16, which is rigidly secured to the arms by braces 17. The connecting members are also secured to the table by hinges, 45 as indicated at 18, and are adapted to fold inwardly with the arms 14. A leg 19 is pivotally secured to each of the arms 14 by a screw bolt or the like, as indicated at 20. A stud 21 is provided on each of the arms 14, 50 which is adapted to enter a hole provided in each leg when the leg is swung into alignment therewith; the legs being adapted to be slightly sprung outwardly to permit the stud

to pass when they are brought into or out of alignment with the arms.

In order to make the table rigid and strong a brace is provided between each pair of end legs. These braces are detachable to permit folding of the table and each comprises a bar member 23 having an enlarged 55 portion 24 adapted to engage and support the table top. On each end of the bar 23 there is secured a channel clip 25, which is adapted to slide upon an arm 15 and leg 19 when brought into alignment with each 60 other, as clearly illustrated in Fig. 3.

A thumb-screw 26, carrying a nut 27, extends through and between the flanges of the channel clips 25, and in each of the leg and arm members there is provided a recess 28. 65 These recesses are positioned so that when a leg 19 and arm 15 are both extended into alignment with each other, the recess in the arm will register with that in the leg. The channel clips 25 may then be slipped over 70 the arm 15 and leg 19; the longitudinal portion of the thumb-screws 26 sliding in the recess of the leg and arm. The thumb-screws 26 may then be screwed up and thereby securely clamp the ends of a brace bar 23 75 between a pair of the end legs.

To further brace the legs 19, two strips 28', preferably of metal, are pivotally connected at their one end to the brace bar 23 by screws 30. The other ends of the strips 80 28 are provided with an opening 31, suitable to receive a stud 32 provided on each of the legs 19, (Fig. 4). As is obvious, when the legs 19 are unfolded and in their extended 85 positions the strips 28 may be swung outwardly and their free ends connected with the studs 32, thereby serving to further brace the legs 19.

At each end of the table top sections 10 and 11 and flush with the edges thereof, 90 there is secured a strip 33, having its inner end slightly rounded, as at 34. On the strips of one section there is provided a hook 35, and on those of the other section there is provided an eye 36 (Fig. 4). These hooks 100 and eyes serve to hold the table together, when folded, as clearly illustrated in Fig. 5. Also, on the underside of the table top section 11 there is secured block members 37 which serve to hold the brace bars 23, when 105 detached from the legs, in a compact and

suitable position for folding, as clearly illustrated in Fig. 4.

When it is desired to fold the table, the braces 28 are detached from the legs. The channel clips 25 are then loosened by unscrewing the thumb-screws 26 and the brace bars 23 removed. Now the arms 15 may be folded inwardly and the legs 19 swung on their pivots to lie in the positions illustrated in Fig. 4. The detached brace bars 23 are now folded one upon the other, as clearly illustrated in Fig. 5, and secured together by means of the hooks 35 and eyes 36, thus forming a very compact unit for shipment or transportation.

While certain features of the present invention are more or less specific in construction, I wish it understood that various changes in the design and proportions may be resorted to within the scope of the appended claims; also that the materials and finish of the several parts employed may be such as the experience and judgment of the manufacturer may dictate and varying uses may demand.

Having thus described my invention, what I claim and desire to secure by Letters Patent is—

1. A combination folding table comprising two main table top sections and an intermediate section to which the first named sections are hingedly secured, a pair of arms hinged to each side of the main table section, a leg pivotally secured to each of said arms and means for holding said legs and arms when extended for supporting the table, said arms being foldable to lie transversely and within the main table top section with which they are associated.

40 2. A combination folding table comprising two main table top sections and an intermediate section to which the first named sections are hingedly secured, a pair of arms hinged to each side of the main table section, a leg pivotally secured to each of said arms, and means for holding said legs and arms when extended for supporting the table, said arms being substantially equal to the width of the main table section with 45 which they are connected and foldable to lie transversely thereof.

55 3. A combination folding table comprising two main table top sections and an intermediate section to which the first named sections are hingedly secured, a pair of arms hinged to each side of the main table section, a leg pivotally secured to each of said arms and means for holding said legs and arms when extended for supporting the table, said arms being substantially equal to the width of the main table section with 60 which they are connected and foldable to lie transversely thereof, and the legs of a like end being adapted to be swung so that each lies longitudinally of the main table

section with which it is associated while the legs of the other end are adapted to be swung so they lie substantially diagonally upon the main table section with which they are associated.

4. A combination folding table comprising a pair of table top leaf sections and an intermediate section to which each of the leaf sections is hingedly secured, a pair of arms hinged to each leaf section, a leg pivotally connected to each of said arms, each leg being adapted to be swung into alignment with the arm to which it is pivoted, means for retaining this alignment, detachable means for holding said legs when in 70 their extended or supporting position, said means comprising a bar extensible between a pair of end legs and having a channel clamp secured to each end adapted to slip over an arm and leg when in alignment with each other and means for securing the clamps against movement when positioned, said means being adapted to positively lock the legs and arms against movement with respect to each other.

5. A combination folding table comprising a pair of table top leaf sections and an intermediate section to which each of the leaf sections is hingedly secured, a pair of arms hinged to each leaf section, a leg pivotally connected to each of said arms, each leg being adapted to be swung into alignment with the arm to which it is pivoted, means for retaining this alignment, and detachable means for holding said legs when 75 in their extended or supporting position.

6. A combination folding table comprising a pair of table top leaf sections and an intermediate section to which each of the leaf sections is hingedly secured, a pair of arms hinged to each leaf section, a leg pivotally connected to each of said arms, each leg being adapted to be swung into alignment with the arm to which it is pivoted, means for retaining this alignment, detachable means for holding said legs when in 80 their extended or supporting position, said means comprising a bar extensible between a pair of end legs, and carrying means whereby it may be secured to said legs.

7. A combination folding table comprising a pair of table top leaf sections and an intermediate section to which each of the leaf sections is hingedly secured, a pair of arms hinged to each leaf section, a leg pivotally connected to each of said arms, each leg being adapted to be swung into alignment with the arm to which it is pivoted, means for retaining this alignment, detachable means for holding said legs when in 85 their extended or supporting position, said means comprising a bar extensible between a pair of end legs and having a channel clamp secured to each end adapted to slip over an arm and leg when in alignment with each other and means for securing the clamps against movement when positioned, said means being adapted to positively lock the legs and arms against movement with respect to each other.

each other, and means for securing the clamps against movement when positioned.

8. A combination folding table comprising two leaf sections and an intermediate section to which both leaf sections are hingedly secured, a pair of arms hinged to each leaf section and foldable upon the underside of said sections, braces between said arms, a leg pivotally mounted on each arm,

and detachable braces between each pair of end legs, said legs when swung to a certain position and said braces when detached being adapted to be within the leaf sections when one is closed upon the other.

In testimony whereof I have hereunto set my hand.

GEORGE R. STINE.
